BY Francis D. Faraday
ATTORNEY.

ATTORNEY,

UNITED STATES PATENT OFFICE

HARRY W. POTTER, OF BIRMINGHAM, MICHIGAN

CARBURETOR

Application filed September 17, 1928. Serial No. 306,383.

The present invention relates to carburetors of internal combustion engines and especially to the construction of the primary mixture forming portion thereof.

5 Among the objects of the invention is to greatly facilitate and lessen the cost of manufacture of such devices without decreasing the efficiency thereof.

Other objects will readily occur to those 10 skilled in the art upon reference to the following description and the accompanying drawings, in which

15 Figure 1 is a partial vertical section through a carburetor embodying the invention.

Figure 2 is a section on line 2—2 of Figure 1, with a part broken away.

20 In the drawings the carburetor is shown as consisting of a float bowl 10 having therein the usual float 11 controlling the inflow of liquid fuel thereto.

This float bowl is surmounted by a mixing chamber shown as constructed of two parts, 12 and 13, of which the upper part 12 is provided with a flanged extension 14 with the flange located at 15 whereby the carburetor is secured to the intake manifold of an engine. The two parts 12 and 13 will be secured together in any suitable fashion as by a 25 30 screws 16 passing through suitable lugs 17.

The mixing chamber is likewise provided with a main air inlet valve, not shown in detail, but indicated by a boss 18. The air inlet valve is provided with a stem 19 through 35 which its movement may be controlled by a lever 20.

The construction, so far described, is conventional and forms no part of the present invention.

40 Leading from the float bowl 10 is a passage 25 controlled by an adjustable needle valve 26. This passage opens at its upper end through a small nipple 27 into a Venturi tube 28, the upper end of which is just below the 45 passage in the extension 14.

Primary air is admitted through a small 50 annular passage 29 to mix with the fuel coming from nipple 27 and passes up into the Venturi tube, while additional air is admitted from the mixing chamber to the lower part of

the Venturi tube through slots 36, formed therein as described below.

The construction of the Venturi tube 28 and the parts immediately adjacent thereto, form the present invention.

Heretofore, it has been customary to form the Venturi tube as an integral part of the portion 13 of the mixing chamber with a cylindrical extension as mounted thereon in order to bring the upper edge to the proper height. This renders the formation of the air passages at the base of the venturi of great difficulty, requiring them to be drilled through the use of difficult drilling operations.

65 In the present construction, the lower part of the venturi indicated at 35 is formed integral with the part 13 and this is then slotted as at 36 down to near the upper end of the nipple 27. The part 35 is formed with a shoulder 37 thereon and is cylindrical on its outer surface. The slots 36 are cut not only in the cylindrical portion but in the shoulder 37.

70 After the slots have been formed, a funnel shaped ring of sheet metal with its lower portion cylindrical and its upper portion flared is slipped over the part 35 to rest on shoulder 37. This ring is indicated at 38 and is of such shape as to form a continuation 75 of the venturi constructed in part by the part 35.

80 The carburetor made in the present fashion operates substantially the same as the conventional carburetor of the same type but is 85 easier and more efficiently made and assembled.

Now having described the invention and the preferred form of embodiment, it is to be understood that the said invention is to be 90 limited not to the specific details herein described and illustrated but only by the scope of the claim which follows.

I claim:—

95 In a carburetor, a two part mixing chamber casing having its lower part in the shape of a shallow pan with an aperture in its bottom wall, a substantially cylindrical elongated, hollow, open ended, boss 35, in said pan and integral with the wall thereof and 100

having slots in its side wall running to the upper edge for providing communication between the interior of said boss and the interior of the pan, and a thin walled, flared, open ended tube mounted on said boss and forming an extension thereof, said tube being so mounted on said boss as to expose a portion of each of said slots and to close the remaining portion of each slot.

10 HARRY W. POTTER.
